CLAIM

The ornamental design for a toy tire ball, as shown and described.

DESCRIPTION

FIG. 1 is a top perspective view of a toy tire ball showing my new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken lines in the figures depict portions of the toy tire ball that form no part of the claimed design.

1 Claim, 6 Drawing Sheets
